UNITED STATES PATENT OFFICE.

WILLIAM G. WOLF, OF PHILADELPHIA, PENNSYLVANIA.

WRITING-DESK.

Specification of Letters Patent No. 13,371, dated July 31, 1855.

To all whom it may concern:

Be it known that I, Wm. G. Wolf, of Philadelphia, in the county of Philadelphia, in the State of Pennsylvania, have invented 5 a new and Improved Desk styled "Self-adjusting;" and I do hereby declare that the following is a full and exact description thereof, reference being had to the accompanying drawings and to the letters of reference marked thereon.

The nature of my invention consists of a double fall A and G hinged on a grooved frame B, supported by a tongue C with a partitioned tray D riding thereon, with horizontal inclined levers E attached to fall A working over any given center F; also an attached fall G hinged to fall A with an upright traveler H working through an upright mortise I on an inclined and declined 15 plane J underneath attached fall G.

By drawing forward the attached fall G dropping on the upright traveler H, then on the declined portion of the plane J, which keeps it from a collision with the integral 20 portions D—viz., tray—and by a back motion the traveler H, then on the inclined

portion of the planes, pushes up the attached fall G clear of the tray, as in Figure 4. Again by a forward motion the inclined levers E underneath fall A and G smaller 30 and greater causes a graduation to the desk. Again by a back motion then the inclined levers underneath falls A and G the greatest working in concert with traveler H on inclined and declined planes J causes the desk 35 to be entirely concealed.

What I claim as my invention and desire to secure by Letters Patent is—

The horizontal inclined levers E and inclined and declined planes J with the upright traveler H working thereon which causes a graduation that of a desk to be formed or else entirely concealed at pleasure as herein described, using for that purpose the aforesaid horizontal inclined levers, inclined planes, and upright traveler.

WILLIAM G. WOLF.
